BUILDING CONSTRUCTION

Albert F. Bemis, Newton, Mass., assignor to
 Bemis Industries, Incorporated, Boston, Mass.,
 a corporation of Delaware

Application July 21, 1934, Serial No. 736,341

5 Claims.

(Cl. 20—1)

This invention relates to an improved building construction, and more particularly to such a construction adapted to employ a plurality of standardized elements capable of being fitted together to conform to a variety of architectural designs and/or room layouts.

More particularly, the present invention is directed to a type of construction comprising standardized pieces or strips, preferably of wood, which may be arranged to interfit with each other and to be readily connected with suitable reinforcing parts, frame members, connecting pieces, and the like. A building of this type is particularly adaptable to a wide variety of uses and is capable of being erected without necessity for employment of highly skilled labor or a variety of skilled artisans. Thus standardized material of this type may be employed by an individual in constructing a camp, garage, shed, or the like, while the material may be also employed by professional builders for more elaborate constructions.

In its essential aspect the present invention makes use of a plurality of standardized strips which may be provided with tongues and grooves so that they may be readily joined in providing panels or sub-assemblies. In many cases such sub-assemblies may be constructed in a manufacturing establishment or shop remote from the building site. Under other conditions the separate strips may be assembled upon the building site.

Ordinarily the panels may be provided with reinforcing parts which may cooperate in affording portions of the reinforcing structure or framework of the completed building. Other frame elements may be arranged to cooperate with these parts of the panels in defining corner posts, posts at wall intersections, sills, girts and the like.

The arrangement of the tongue and groove connections of the component elements may be supplemented with splines arranged to interfit with grooves upon certain of the elements so that wall structures may be provided typically consisting of a single essential layer of material which, due to the tongue and groove and spline connections, affords its own seal intermediate the surfaces of the wall. The fastening means securing the component elements together preferably may be arranged in the plane of the tongue and groove connections, thus ordinarily being concealed and protected from exposure to the weather.

Preferably nails may be employed for this purpose and the major portion of the component elements may be relatively small in cross section so

that closely spaced joints are provided therebetween; accordingly an arrangement is afforded whereby the natural tendency of wood to contract or expand due to changes in humidity may be automatically compensated for by the individually nailed joints without necessitating a change in the over-all dimensions of the wall. Thus such construction avoids casting heavy strains upon parts of the wooden building structure, such as corner joints, due to expansion and contraction of the elements. Preferably, however, the component elements or lumber of which the building is constructed may receive a suitable treatment to afford waterproofing or water-resistant qualities.

In the preferred embodiments of the invention the various parts may have a modular relationship to each other of the general character disclosed in my United States Patent No. 1,878,367, issued September 20, 1932. Thus the body portions of panels may comprise units of generally square cross section while the margins of the panels may be provided with reinforcing members having cross-sectional dimensions which are multiples of the corresponding dimensions of the intermediate or substantially square units. This arrangement results in the provision of panels having body portions with surfaces located reentrantly in relation to the corresponding surfaces of the reinforcing members, thus defining spaces which may be filled with insulating material or covered with an outer layer of finishing material to afford an air chamber for insulating purposes.

bly of girts and floor parts at the corner of a building of the type disclosed in Fig. 1;

Fig. 12 is an isometric view similar to Fig. 1 but showing an optional embodiment of the invention;

Fig. 13 is an isometric view similar to Fig. 2 but illustrating the arrangement which may be employed with the embodiment of the invention shown in Fig. 12;

Fig. 14 is an isometric view of the end portion of a sill assembly such as is shown in Fig. 12;

Fig. 15 is a view similar to Fig. 10 but showing a floor panel assembly of the type illustrated in Figs. 12 and 13;

Fig. 16 is an isometric view of a wall panel assembly such as is employed in the type of construction illustrated in Fig. 12;

Fig. 17 is a broken isometric view with parts removed and parts shown in section illustrating a third embodiment of the invention;

Fig. 18 is a cross-sectional view of a core strip employed in the various constructions illustrated herein;

Fig. 19 is a similar view of an optional type of filler piece; and

Fig. 20 is a similar view of another special form of filler piece.

Fig. 1 of the accompanying drawings illustrates a portion of a building structure erected in accordance with this invention. Such a structure may be provided with any suitable foundation 1

formed of concrete or the like upon which keying strips 2 of metal may be arranged to provide up-standing ribs to interfit within grooves in the sill assembly. Such an assembly may comprise an outer elongate element 4 and two inner elements 5 and 5^a which have mutually registering grooves in which a spline 6 is disposed. An intermediate element 7 is provided with a smaller vertical

depth than the remainder of the sill assembly so that upper and lower grooves are provided, the lower groove receiving the rib of the keying strip 2. The strips 4, 5 and 5^a preferably are secured to the intermediate strip 7 by any suitable means,

as by nails or screws. These various parts may be formed of standardized stock and secured to each other in a suitable shop remote from the building site. The upper groove provided by this sill assembly is arranged to receive the ends of

the wall panels 10. At the sides of the building the members 5^a may be omitted from the sill assemblies so that the upper surfaces of the members 5 afford ledges to receive ends of the floor members.

Such a panel is illustrated more particularly in Figs. 3, 8 and 9 of the accompanying drawings and comprises a plurality of wooden core strips 11 which preferably may be of generally square cross section having interfitting tongues and grooves and being secured to each other by any suitable means such as glue and/or nailing, preferably the latter. Thus, as shown in Fig. 8, nails may be disposed in the central planes of the strips forming the panel to secure the tongued and grooved portions thereof in proper interfitting relation. As is evident from Fig. 9, the nails 13 connecting the various strips 11 may be arranged in vertically spaced sets so that a worker familiar with a panel assembly of this character

may be able conveniently to saw between the sets of nails to enable portions of the panels to be cut away to accommodate fittings or attachments, for example to accommodate window casings.

Suitable reinforcing elements 12 may be arranged at each side of the panel, these elements

being suitably grooved so that at one side of the panel the tongue of the adjoining core strip 11 is received in the groove while at the opposite side of the panel a spline 14 may be employed, the parts 12 also being secured to the strips 11 as by nailing. The outer surfaces of the elements 12 are provided with grooves 16 to engage other parts with which the panel may be assembled. The elements 12 may be substantially thicker in a direction transverse of the panel than the strips 10, for example, as shown they may have a thickness three times that of the strips, but their upper and lower ends may be cut away to provide a thickness similar to that of the strips 11. Thus the panel is in effect provided upon its upper and lower edges with tongues which have the same thickness as the strips 11.

Preferably transverse members 15 extend between the elements 12, these members 15 being disposed at the upper and lower ends of the panel 10 and upon both faces thereof, their surfaces being in coplanar relation with the rabbeted ends of the elements 12, as illustrated, for example, in Fig. 9. Preferably, as shown, the members 15 may be connected by nails to each of the strips 11, thus serving accurately to position the center of each strip in relation to the transverse members 15. An arrangement of this character is particularly desirable when air-dried lumber is employed, since the individual shrinkage of the wooden elements which may occur is readily taken up by the tongue and groove connections, the square cross-sectional shape of the strips 11 permitting the provision of these connections at close intervals so that the change in relative dimensions of the panel as a whole may be negligible despite marked changes in humidity.

It is furthermore to be noted that the elements 15 may have the same cross-sectional size as the square body portions of the strips 11. Thus the cross-sectional dimensions of all of the parts of a panel 10 have a definite relationship to each other, being equal to the cross-sectional dimensions of the square body portions of the strips 11 or being an integral multiple thereof as is the case with the elements 12 which have one cross-sectional dimension equal to the side of the square body portion of a strip 11 and the other cross-sectional dimension equal to three times said side dimension.

It may furthermore be noted, as particularly illustrated in Fig. 18, that the tongues and grooves of the strips 11 also preferably have a definite dimensional relationship to the modular dimensions of the strip itself. Thus the groove may have a width equal to one-third of the width of the strip and have a depth substantially equal to or slightly greater than one-half of its width, the tongue obviously being dimensioned to fit into the groove of an adjoining similar strip with a nominal clearance.

It is evident that the arrangement of the tongue and groove connections, including that afforded by the spline 14 and the cooperating grooves, permits the panel 10 to consist in general of a layer of wooden parts arranged to have weather sealing connections with each other. This same general arrangement of weather sealing connections by tongue and groove or splined joints, as well as the general modular relationship of the parts, may be employed throughout a building constructed in accordance with this invention.

If desired, the ends of the strips 11 and 12 may be grooved, as designated by numeral 17 in Fig. 3.

It is thus evident that a panel 10 is adapted to be assembled in interfitting relation with adjoining parts in a variety of ways. Thus, as shown in Fig. 1, the lower portion of the panel 10 fits within the upper groove provided by the sill assembly 4, while, if desired, a groove in the member 7 of this assembly may receive a suitable spline to engage the lower groove 17 in the component elements of the panels 10. Thus it is evident that the lower portions of the panels 10 may be firmly interfitted with the sill assemblies. Nailing, however, may be employed also, particularly to aid in securing the reinforcing parts 12 to the side pieces 4 and 5 of the sill assemblies.

15 Between the panels 10 filler strips 12^a may be provided which are similar to the strips 12, suitable splines 14 being disposed in the registering grooves of the strips 12^a and of the intervening strip 12. These parts may also be connected to each other by nailing. Thus the reinforcing elements 12 of adjoining panel assemblies cooperate with the intervening filler piece 12^a in forming a vertical frame element or stud portion of the wall assembly.

20 If desired, the optional filler piece 12^f illustrated in Fig. 19 may be employed in place of a filler strip 12^a. The member 12^f may consist of two parts of wood separated by a saw kerf 100. In practice the splines 14 may be secured, as by 25 gluing, to one of the halves of this filler piece, and after the adjoining parts of the wall have been assembled the remaining half of the piece may be located in place and nailed to the portion first assembled with the wall. As illustrated in Fig. 19, 30 the complete filler piece has a cross section similar to that of the member 12^a. This arrangement facilitates the assembly of the wall structure, particularly if the parts of adjoining panels are not precisely in proper position.

35 At corners and wall intersections the post assemblies P (Fig. 4) may comprise outer elements 12^a and 12^e and an intermediate element 12^b (Fig. 4) which is similar to the element 12^a but which is provided with grooves 20. The element 12^a is 40 similar in form to the filler strips 12^a of the stud assemblies, while the part 12^e is similar to the part 12^a, but lacks the tongue-like end portions of the latter. The parts of this assembly are joined to each other by splines 14 and nailing. Ordinarily the post assemblies may be supplemented by thin filler elements 12^c having a thickness, for example, of one-half that of the elements 12^a but being arranged in interfitting relation with suitable splines associated with the elements of the post assembly and with the elements 12 of the adjoining panels.

45 Fig. 4 illustrates in greater detail the construction of such a post assembly P, it being evident that the ends of the elements 12^a and 12^b afford a tongue-like corner portion, provided with spline-receiving grooves, which is adapted to be engaged with the sill assemblies and with similar portions of the superstructure forming the girt assemblies for the second story or the plate assembly for the roof.

50 As shown in the upper part of Fig. 1, such a post assembly P may be arranged to afford a three-way connection for walls by the provision of three thin filler pieces 12^c associated with the respective reinforcing elements 12 of the three adjoining panel assemblies 10.

55 In certain cases an internal wall may be provided by the core elements 11 without arranging the same in panel assemblies 10; such constructions may be employed, for example, for a light

partition such as is suitable for a closet. With such an arrangement the stud assemblies may be of the general type previously described, with the exception that the filler element 12^a is replaced by a similar element 12^d which has less depth transversely of the wall so that it cooperates with the adjoining elements 12 in defining a groove to receive one of the elements 11 to which a row of similar elements is connected to define the internal partition. With this arrangement the ends 10 of the elements 11 may be connected to the adjoining wall, floor and ceiling structures as by 15 diagonally directed nailing. Rather than the element 12^d, an element 12^h such as illustrated in Fig. 20 may be employed. This element 12^h is of generally rectangular cross section, having a cross-sectional area equal to one and one-half times that of the body portion of a strip 11 and having its corners rabbeted as shown to receive splines 14 which may be glued in place. Before 20 or after this element is assembled in the wall, a retaining plate 101 may be secured by screws to the inner face of the wooden element, this plate being provided with flange portions to engage the corners of the splines 12, as illustrated.

25 The floor assembly may be formed of panel assemblies 10^a including strips 11 assembled with edge reinforcements 12^e. Preferably the panel assemblies 10^a are made in the shop or manufacturing establishment, wooden strips 22 being secured to the ends of the strips 11 and extending between the ends of the elements 12^e, as illustrated in Fig. 10. Reinforcing strips 21 may also be disposed between elements 22. The floor panels 10^a which are thus provided may be associated with joist members 24 (Fig. 5) which have grooves formed in their side faces to engage tongues upon strips 11 which are secured beneath the assemblies 10^a. Thus a typical joist assembly is provided by the elements 12^e of the panel assemblies 10^a by the intervening member 24 and by the adjoining strips 11 (Fig. 1). The ends of these strips 11 and of the member 24 rest upon the elements 5 of the sill assemblies at either side of the building. At the front and rear of the building, filler pieces 26 may be arranged to provide grooves engaging strips 11 (Fig. 7), which are disposed beneath the adjoining portions 12^e of the adjoining floor panel, these parts being connected to each other and to the sill assembly by 30 nailing. It is evident that the width of the member 26 corresponds to that of a narrow filler strip 12^c and permits the modular relationship of the various elements of the floor and wall to be retained. Thus, as shown in Fig. 1, the vertical joints of the wall panels coincide with the horizontal joints of the floor structure.

35 A floor construction of this general type is advantageous in that each of the elements 11 aids in reinforcing the joist members. Thus all parts 40 of such a floor, due to the tongue and groove and splined connections, are connected to each other to afford mutual reinforcement. Furthermore, the arrangement of the members 12^e and 24 affords a construction for the joists which avoids the 45 necessity for but performs the function of the conventional bracing which is commonly employed with floor joists.

40 In certain cases it may be desirable to provide an internal sill element to support a partition in 50 the manner illustrated at the right of Fig. 1. Such a sill element may comprise members 5 arranged at opposite sides of an intermediate part 7^a which does not provide a groove at the bottom of the sill but does cooperate with the elements 55 75

4 in providing a large groove to receive the ends of strips 11 and 12 of the internal wall; the part 7^a also provides a smaller groove engageable with a suitable spline that interconnects the sill assembly with the grooves 17 of the wall panels 10 in the manner already described.

Figs. 2 and 11 illustrate the arrangement of a girt assembly which may be associated with a second floor including panel assemblies 10^a arranged 10 in the general manner already described. The girt assembly may include an outer piece 4 similar to that of the sill assembly and an intermediate piece 31 (Fig. 6) provided with upper and lower grooves 32 capable of receiving splines. Thus the 15 lower groove of the element 31 may receive a spline 33 engageable in the groove 17 at the upper ends of the wall panel 10. The inner portion of the sill assembly is provided by a member 34 which cooperates with the elements 4 and 31 in defining a large groove to receive the ends of the strips 11 and 12 of the lower wall assembly. The 20 upper portion of strip 34 is provided with a groove to receive a spline 36 that also engages a small floor spacer strip 11^a which is substantially square 25 in cross section. The crosspiece 22 of a floor panel 10^a may be disposed upon the strip 11^a (Fig. 11) and cooperate with the elements 4 and 31 in defining a large groove to receive the lower 30 ends of the strips 11 and 12 of the wall panel assemblies of the succeeding story and cooperating parts.

At the side of a floor panel a construction quite similar to that employed with a sill assembly may be employed, the member 34 of the girt assembly 35 having a splined connection with an element 5, which is similar to the element 5 of the sill assembly, and a filler element 26 being disposed between the member 12^a of the floor panel and the element 5, as shown at the left of Fig. 11.

40 The type of girt assembly which may be employed with a major internal partition is similar to the internal sill assembly illustrated at the right of Fig. 1, except that the parts are arranged so as to provide a bottom groove to receive the upper ends of the strips 11 and 12 of the internal partition.

It is evident that the parts of a building construction of this type may be cut as desired to provide openings for doors and windows and that 50 they may readily be associated with a conventional or any suitable roof structure. Thus a construction of the type disclosed herein may be employed in combination with a conventional frame building, as, for example, to provide an addition or extension upon such a building.

Obviously a building of the type described may be provided with any suitable flat or pitched roof, and the elements 11 and 12 may, if desired, be left uncovered and exposed to the weather, or 60 suitable layers of finishing material may be applied to the exterior or interior surfaces of the walls. In the latter case suitable pockets are provided adjoining the strips 11 and between the members 12 which may be left vacant to afford 65 air pockets for insulation or which may be filled with any suitable insulating material. Obviously a construction of this type is adapted to be employed in combination with conventional frame buildings when desired, as, for example, to provide 70 additions to the latter, and is adaptable to cutting to permit variations in design arrangement of door and window openings, provision of closets, openings for registers and the like.

In practice many of the strips 11 rather than 75 extending for the full height of the panel may

be formed of short pieces which are held in spliced engagement due to the tongue and groove connection with adjoining strips. Thus this invention affords the economy of permitting the employment of short pieces of wood that ordinarily 5 might have little commercial value.

Obviously many of the parts of such a building may be preformed in a manufacturing establishment, certain parts being joined in assemblies such as wall panel assemblies, sill and girt assemblies; floor panel assemblies, and the like. The parts may preferably be formed by automatic machinery to close dimensions so that a modular relationship is maintained between the various component elements which are employed 15 in a building system of this character. Thus the strips 11 have a square cross section, the tongue of the strip projecting beyond the square portion thereof and the groove of the strip being reentrant within the square portion. This square 20 body portion of a strip 11 may be regarded as defining a module which determines the cross sections as well as in many cases the lengths of the component members of the assembly. Thus the members 12, 12^a and 12^b each have one cross- 25 sectional dimension conforming to that of a strip 11 while having a transverse cross-sectional dimension equal to three times that of the strip 11. On the other hand, the members 12^c have a cross-sectional dimension which is twice that of 30 the strip 11 while the members 4, 5 and 7 have a thickness like that of the strip 11 but have depths which are multiples of the cross-sectional, modular dimension of a strip 11. The filler strips 12^c have one dimension equal to three times the 35 modular dimension of the strip 11 and a transverse dimension equal to one-half of the modular dimension.

It is furthermore evident that the arrangement of the grooves upon the larger pieces such as the members 12, 12^a, 12^b, etc., has a modular relationship to the dimensions of a strip 11. Obviously when a groove is formed upon the narrower face of such a member, it is located centrally of the member in a position corresponding 45 to the groove of the strip 11. When a groove is located upon a wide face of such a rectangular member, its central portion is either spaced from one edge of the member at a distance equal to the spacing of a groove from a side of the strip 50 11 or at a multiple of this dimension. Thus in the case of a member 12 the central portion of a groove is spaced from the faces of the member at a distance equal to one and one-half times the modular dimension afforded by the side of a body 55 portion of a member 11, while in the case, for example, of a floor member 24, the groove is located at one-half of this modular distance from one edge of the member and at two and one-half times this distance from the opposite edge. 60

It is thus evident that the various parts of a building of this character may be suitably standardized and provided with interrelated modular dimensions, which permit a high degree of flexibility in construction without necessity for 65 cutting to special dimensions, although these elements may be readily cut if desired.

In certain constructions, it is preferable to arrange the wall panels so that the strips 11 extend horizontally. Thus, as shown in Fig. 16, a 70 panel assembly 40 may be provided by a plurality of strips 11 arranged horizontally with their tongued and grooved portions in interfitting relation. Vertically disposed boards 41 may be secured to the faces of the end portions of these 75

strips, thus affording suitable reinforcements. In certain cases, particularly when panels of this character are to be employed for external walls, the boards 41 may be secured upon one face only 5 of the assembly of strips 11, or the boards 41 may be removed from one face of the assembled strips before the panel assembly is disposed, for example, in an external wall. When the assembly is to be employed in an internal wall, the boards 41 10 are ordinarily provided and retained upon both faces of the assembly.

With this construction a composite sill of the type illustrated in Fig. 12 may be employed, such a sill comprising an outer plate 4, an intermediate 15 plate 43 providing a horizontal groove 44 and inner members 45 and 45^a, the latter providing grooves at its sides, one of which may be associated with a spline 58 fitting into a portion of the floor assembly. A spline 46 may be secured in 20 the groove 44 and may engage a groove in a plate 48 which overlies the members 42, 43 and 45^a. This plate 48 may have the same general cross section as the elements 12 shown in Figs. 1 and 3.

A second spline 49 may be disposed in the upper groove of the element 48 to engage a groove in the lower element 11 of a wall panel. Inner and outer pilasters 50 and 52 may be arranged to engage the end portions of wall panel assemblies 40, thus cooperating in providing vertically disposed frame elements. Thus the end portions 25 of two panel assemblies may be arranged in abutting engagement with the boards 41 received in a groove in a vertical member 50, these grooves having a width of the order of twice the width 30 of a single board 41.

A grooved element 50^a may have a groove wide enough to engage one board 41 and be arranged to cooperate with other parts in providing a post assembly, such as assemblies P¹ and P², illustrated 40 in Fig. 12. Thus at an external corner, outer frame elements 52 and 64 (the latter being of the same cross section as elements 41) may be arranged in planes at right angles to each other to define the external portion of the corner portion; the lower ends of these elements resting 45 upon the outer portion of the sill plates 48. Filler pieces 65 and 65^b may be disposed in the planes of the strips 11 of the adjoining wall panel assemblies and the grooved element 50^a may be engaged with the end portion of one of these assemblies, while a similar, but narrower element 50^b may be similarly engaged with the end portion of the other assembly. The various parts of 50 such a composite post may be secured to each other and to the adjoining parts by nailing, being arranged as shown in Fig. 12.

The post assembly P² is provided by an outer plate or element 64, a filler element 65^a in the planes of the strips 11 of adjoining panel assemblies with grooved elements 50^a and 50^b engaging the ends of the adjoining wall panel assemblies and with a filler element 65^b in the plane of the internal wall, these parts being secured to each other and to the external and internal 65 sill assemblies by nailing, thus providing a composite three-way post connection.

With this embodiment of the invention the internal sill member may be of the type illustrated at the right of Fig. 12, comprising two outer elements 57 connected by splines 53 with an intermediate element 54 having its upper portion cut away to provide a groove receiving a spline 46^a engageable in a plate 48 similar to that employed for the external sill assembly. The floor 70 panel assemblies (Fig. 15) employed with this

embodiment of the invention may comprise a plurality of strips 11 with side members 57 provided with grooves to receive the tongue of one of the strips 11 at one side of the assembly and receive a suitable spline 58 at the other side of the assembly which is engaged within the groove of the adjoining strip 11. As shown in Fig. 12, these floor panel assemblies may be arranged with their side pieces 57 in juxtaposition and provided with an interconnecting spline 60; at the sides of 10 the floor, as illustrated in the lower part of Fig. 12, the adjoining side pieces 57 may be similarly connected by a spline 58 to the grooved member 45^a of the sill assembly, the members 45^a and 57 having a similar cross section. 15

Fig. 13 illustrates the construction shown in Fig. 12 as assembled with the girt portions and second floor of a building. The pilasters 50 and 51 may be secured as by nailing to plates 48^a which are similar in cross section to the plates 20 48 of the sill assemblies. In the external girt assemblies these plates 48^a may receive splines 49^a connecting the former to the inner element 70 of the girt assembly, while an outer element 71 may be secured, as by nailing, to the outer 25 marginal portion of each external plate 48^a. An upper plate 48^a may be connected by a spline 49^a to the element 70 and may be connected, as by nailing, to the elements 70 and 11. Thus the upper and lower plates 48^a cooperate with the 30 members 70 and 11, particularly the former, in defining a groove to receive the ends of the floor panels, which may be similar in construction to those shown in Fig. 15, the ends of parts 11 and parts 22^a of these panels being disposed in the 35 grooves thus provided by the sill assemblies.

The girt arrangement for an internal wall such as is illustrated at the right of Fig. 13 may comprise a lower plate 48^a having a spline connection with a girt element 54 of a girt assembly of 40 the same type as the internal sill assembly provided upon the first floor and described supra.

Fig. 17 illustrates a further adaptation of the invention wherein the strips 11 are generally disposed in horizontal planes. With this construction the floor, sill and girt assemblies may be of the same general type as illustrated in Figs. 12 and 13 and described with reference to those figures, and the internal walls may be similarly built up of panel assemblies 40. The external 50 walls, however, are provided by assemblies each including a plurality of horizontally disposed strips 11 with upper and lower reinforcing elements 80 connected to the strips 11 by tongued and splined connections. The reinforcing members 80 extend outwardly beyond the strips 11 55 having substantially twice the thickness thereof in accordance with the preferred embodiment of the invention.

The panel assemblies thus provided may be 60 assembled in the manner illustrated in Fig. 17 so that the strips 11 and the members 80, which may be similar in cross section to elements 12^d of Fig. 1, define continuous planar surfaces for the interior of the building, while the strips 80 65 of adjoining panel assemblies are disposed in juxtaposition to afford horizontal ribs for the outer walls. At the corners of the building and at intervals therebetween filler members 83 may be provided, if desired, to afford a further reinforcement of the structure. At the bottom of such a wall assembly the member 80 of the lower panel assembly receives a spline 49 of the sill assembly. At the top of an external wall a similar arrangement may be employed, a spline 49^a 75

affording a connection between the member 80 of the upper wall panel assembly and the plate 48^a of the girt assembly. At internal corners vertical strips 90 may be secured to the ends of 5 the elements 11 of an internal wall and the ends of the elements 11 and 80 of the external wall. Obviously with this form of the invention, as with the other forms of the invention, the various juxtaposed or abutting parts are ordinarily 10 secured to each other by means such as nailing in addition to the tongue and grooved or splined connections.

From the foregoing it is obvious that the present invention permits the provision of a system 15 of building elements which may be economically manufactured in quantities and may be assembled in accordance with a variety of arrangements while permitting conformity to a wide variety of architectural designs. In fact, 20 the flexibility of construction permitted by these parts makes them convenient for employment in constructing articles of furniture such as beds, tables, closets, or the like, which may be either built into or removable from the building in 25 which they are located. Obviously the modular relationship of the dimensions of the elements permits them to be employed in a wide variety of relationships, only a few of which are illustrated herein. The essential portions of the 30 building construction may be arranged to afford an effective weather seal and to permit simplicity of construction so that little, if any, skilled labor is required, particularly if a small building is being erected. On the other hand, 35 a construction of this character may be employed with suitable conventional or special finishing panels and insulating arrangements where a more elaborate construction is desired. Furthermore, the arrangement of the tongue and 40 groove and splined connections, particularly when nailing is employed, permits wood to be used without undesirable strains resulting from expansion and contraction due to changes in humidity.

45 Since the spline connections are in general the mechanical equivalents of the tongue and groove connections, the term "tongue and groove" in the following claims is to be construed to cover splined connections, unless clearly inconsistent 50 with the context. It should be understood that the present disclosure is for the purpose of illustration only and that this invention includes all modifications and equivalents which fall within the scope of the appended claims.

55 I claim:

1. Panel assembly comprising a plurality of 60 wooden strips with interfitting tongues and grooves, and reinforcing members extending along the edges of the assembly and secured to the strips, said members being grooved, one of 65 said members having a groove in interfitting engagement with the tongue of the adjoining strip, and a spline fitting in a groove of the other member and in a groove of the adjoining strip, said strips being assembled in coplanar relationship, each of said members having a thickness greater than that of the strips and extending beyond the plane thereof, the ends of said members having a thickness of the order of that of the strips, where- 70 by the ends of the assembly may be received in grooved frame members.

2. Panel assembly comprising a plurality of wooden strips with interfitting tongues and grooves, and reinforcing members extending along the edges of the assembly and secured to the strips, said members being grooved, one of 5 said members having a groove in interfitting engagement with the tongue of the adjoining strip, and a spline fitting in a groove of the other member and in a groove of the adjoining strip, said strips being assembled in coplanar relationship, 10 each of said members having a thickness greater than that of the strips and extending beyond the plane thereof, the ends of said members having a thickness of the order of that of the strips, whereby the ends of the assembly may be received in grooved frame members, the ends of 15 said members and of said strips having aligned grooves defining an elongate groove at the end of the panel to receive a spline or the like.

3. Building construction comprising frame 20 members providing grooves, panel assemblies extending between the frame members, each of said panel assemblies including similar strips having substantially less thickness than the frame members, and reinforcing members extending transversely of the strips adjoining but in spaced relation to the ends thereof so that the ends of the strips extend beyond the reinforcing members to provide tongues, said tongues being received in the grooves of the frame members and said reinforcing members being juxtaposed to the faces 25 of the frame members at either side of the grooves thereof.

4. Building construction comprising frame 30 members providing grooves, panel assemblies extending between the frame members, each of said panel assemblies including similar strips having substantially less thickness than the frame members, and reinforcing members extending transversely of the strips adjoining but in spaced relation to the ends thereof so that the ends of the strips extend beyond the reinforcing members to provide tongues, said tongues being received in the grooves of the frame members and said reinforcing members being juxtaposed to the faces 35 of the frame members at either side of the grooves thereof, small aligned grooves in the ends of the strips and corresponding small grooves in the inner walls of the grooves of the frame members, 40 and splines disposed in the small grooves at the ends of the strips and the small grooves of the frame members, thereby to afford an effective seal between the panel assemblies and frame members.

5. Building construction comprising panel 45 assemblies having body portions consisting of strips having a modular thickness, reinforcing members extending transversely of the strips adjoining but in spaced relation to the ends thereof so that the ends of the strips in effect afford tongues 50 at the ends of the assemblies, composite frame assemblies comprising plates each having a modular thickness similar to that of the strips, said plates being arranged so that an intermediate plate has less depth than the adjoining plates to define a 55 groove having a width corresponding to the thickness of the tongue portions, the tongue portions being received in the grooves thus provided by the frame members.
